John Martineau. Elbridge N' York
Letters Patent

The schedule referred to in these Letters Patent and making part of this
specification containing a description in the words of the said John Marti-
neau himself of his improvements being a composition of mallets de-
signed for and is applicable to the construction of Roads Streets &c &c
which he calls the American plan of Road making.

To whomsoever these presents shall come

Be it known that at John Martineau of the Town of Elbridge
County of Onondaga and State of New York have invented a new and
useful composition of mallets designed for and applicable to the construc-
tion of roads streets and highways which it is believed constitutes
a valuable improvement on the McAdam plan and others now in
use. The following is a full description of the composition of mallets
and mode of using the same in the construction of Roads Streets &c. as
concrete by same. The composition consists of two substances
simply or combined with turpentine or other substances of a cohesive
nature and sand of different degrees of coarseness combined together
so the composition may consist of one quality of sand with two
or other cohesive cement. Other varieties of combination may be
used according to the exigencies of the case. Determined by the section of
country where a road on this principle is proposed to be constructed.
The varieties may consist of gravel coarse or fine with
the interstices filled by sand. It may have but one
or that in all cases the combination of hard substances to be compacted
with the two or other cohesive cement should present the small
est amount in the aggregate of interstices or minute cavities to be
filled by cement. Cobble stones may be used or broken stones
such as are used on a McAdam road whatever kind or variety
of materials are selected in any particular case the whole should

be rendered as compact and uniform as possible. Of coarse materials enter into the composition in any case, fine materials should be combined therewith to fill the spaces and the mass, which and compact until the upper surface smooth and even so as that after it has been grouted with Tar or other cohesive cement it may present a surface quite smooth and uniform.

Hearing described what constitutes the composition intended to be used in this improved mode of constructing Roads, Streets &c over them now in use which improved mode for the sake of distinction will designate as the american plan of Road-making. I now proceed to describe the mode of construction — The same or similarly suitable modes are to be followed in this case as for the McAdam Road. It is first to be staked out the grades or gradients, the necessary precautions taken by Culverts, side ditches and drains to collect and carry off the water. The bed of the road is to be rendered forward compact by Rolling or other suitable process preserving the shape the face of the road is intended to have. Then it may be remarked as this combination is impervious to water much more perfectly than a McAdam covering it is not necessary to be so much raised or convex to shed the water as his plan makes proper and necessary.

The Road or Street being laid out, graded and rendered compact and firm is now ready to receive the covering to be considered. The simplest material in a large section of the United States is sand which it is known from the best foundation free of expense cost. The sand is spread over uniformly to the required thickness, say three inches in ordinary cases. The proportion which will somewhat depend on the nature of the soil constituting the bed of the road. If it is fine and homogeneous and holding water easily than the covering may be diminished to a minimum — In a work the cover to be deposited may be in thicknesses from one inch to six according to circumstances the cover being put on and shaped correctly according to the side ditches of running and even to form double walls it is right to be

cemented. Fair weather should be selected for this operation.
 If tar alone is used and in a warm latitude it may be required
 to boil it a little to diminish its fluidity, and prevent its
 yielding to ordinary weights. Though it is believed that raw
 pure tar will wet the sand, or sand commixed with other
 hard material, soon as sufficiently firm hard compact mass to
 resist injurious impression from the impinging force of vehicles either
 six feet and leave unimpaired its character for great durability
 by wear still it may be found useful to boil or heat the
 tar to a suitable degree as a means of making it pervade the
 whole mass to be cemented more readily and effectually than
 when cold or in its natural raw state. Among others this method
 may be employed to distribute the cement over the face of the road
 for. a batter may be provided with a reservoir of tar and a
 perforated cylinder laying near the face of the road horizontally
 connected with the reservoir. The communicating tube between
 the reservoir and the perforated cylinder provided with a cock
 or stopper. Now the reservoir being supplied it may be moved
 by a horse to a suitable place to begin the process of cementing
 the face of the road. Then the cock being turned the fluid
 descends to the perforated cylinder and passing out of the numer-
 ous orifices or holes is let on to the face of the road in the required
 quantity the cock concern moving gradually along, depositing
 as much as the face of the road will absorb till it is adhes-
 tive quite to the extreme upper surface. After having gone
 over once my first examination is found to be sufficient it
 must be supplied. The perforated cylinder must be long enough
 to extend across the road if it be narrow, or the width of
 the road may be divided into several spaces or swaths and each
 in succession be cemented. The wheels of the cart may rest on
 flat stones prevent them from impaling the surface. Other
 methods may be adopted to put on the cement. Travelling some-
 thing like the rattling Job carried by hand may be used

use of, others may suggest themselves. It is by no means a difficult operation.

Sidewalks in Cities and Towns and footways in villages and country places, walks in pleasure ground and paths may also be made on this plan. The accompanying drawing shows some of the modes in forms according to which roads and streets may be constructed. In Fig. 1. & Fig. 2. A A are sidewalks supposed to be made of the same materials as the crossing of the carriage way. B B are curb stones. C in Fig. 1 represents a thin covering over the broken or rubble stone of a Macadamized street. E represents the natural earth in all the figures. CC in Fig. 2. represents the covering to consist of pebbles, gravel and sand all cemented over D D a mass of cobble stone gravel and sand forming the Bed of the Street. In Fig. 3. G G represent the cemented covering to consist of pebbles, gravel and sand about three inches thick. E F represents sidewalk paved with common cobble stone. The road in this figure is raised pretty high and is supposed to be located on a springy or wet soil. Fig. 4 may represent a street or road. H H the sidewalk I I gutter J J the carriage way of the Street or road covered continuously with cemented sand. Fig. 5. represents a common road where the carriage way only is covered with the cemented composition represented by K K and terminating at L L. In this case the sidewalk is formed in the common soil which overlaps a little the ends of the cemented composition to protect it from abrasion at the edges. This is the cheapest form of road. It is proper to remark that in some situations such as before the bed or embankment of the Street or road, made of cemented materials such as sand and gravel cemented with a hydraulic lime or any other common cement, none of which will answer well for the bearing surface of the road being of a nature too friable, but by being covered in the way here proposed may form a road of additional value and durability. What I claim as my invention and improvement is the application of the last mentioned or any of the steps of various other inventions already known to a paved

507 411.

state and that state used as a cement to apply to and combine with Sand Gravel Pebbles, Gobions, Stones such as used for a McAdam Road, or cobble stone the interstices of coarser materials being in all cases filled as well as may be with sand and gravel and cemented with tar or turpentine to form the wearing face or surface of streets Roads &c in the manner described in this Specification how ever the same may be modified or varied in execution

I also claim the application of the before mentioned cohesive substances combined with sand or other material to the lining of Canals, reservoirs, floors, reservoirs, Cisterns &c &c in all of the varied forms which practice may suggest however modified or varied.
